Primary Examiner — Jae Liang*Assistant Examiner* — Bryan C Gusman(74) Attorney, Agent, or Firm — Jose Cherson Weissbrot(57) CLAIM

The ornamental design for a table with extendable tabletop, as shown and described.

DESCRIPTION

FIG. 1 is a front, right, top perspective view of a table with extendable tabletop, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a front, right, top perspective view of the table with extendable tabletop in an alternate configuration.

The dashed broken lines in the figures are for the purposes of illustrating portions of the table with extendable tabletop and form no part of the claimed design.

1 Claim, 9 Drawing Sheets(56)
